UNITED STATES PATENT OFFICE.

FRANCIS EPPS RICHARDSON, OF SAVANNAH, GEORGIA.

CABINET FOR LACES AND THE LIKE.

1,121,132.

Specification of Letters Patent.

Patented Dec. 15, 1914.

Application filed July 22, 1912. Serial No. 710,800.

To all whom it may concern:

Be it known that I, FRANCIS E. RICHARDSON, a citizen of the United States, residing at Savannah, in the county of Chatham and 5 State of Georgia, have invented certain new and useful Improvements in Cabinets for Laces and the like, of which the following is a specification, reference being had therein to the accompanying drawing.

10 A leading object of this invention is to provide a compact cabinet capable of holding in convenient form for display a great quantity of laces or the like.

With this end in view a rotary receptacle 15 having glass doors is mounted on a base structure and has on two opposite sides a series of closely contiguous vertical frames each provided with lace racks and each adapted to be drawn out edgewise and 20 swung 90° so as to present its broader open side to the persons inspecting the goods.

In the drawings, Figure 1 is a front elevation of the apparatus, the front doors being opened and partly broken away. Fig. 2 25 is a view looking from the right in Fig. 1, part of the apparatus being shown in axial section. Fig. 3 is a plan view, the top of the rotary receptacle or casing being removed. Fig. 4 shows in side view the upper portion 30 of one of the frames with the upper lace rack therein. Fig. 5 illustrates the mounting of the rack in the frame. Fig. 6 is a detail view showing the connection of the rack bar to one of its end supports.

35 In these figures, A represents a base structure consisting of a suitable casing having a plane top A' and, below it, drawers A² upon two opposite sides. From this base rises a central rod B rigidly fixed to a cross bar B' 40 in the base below the plane of the drawers. On this base supported by rollers C⁰, stands the lace receptacle or casing C provided with side walls C', front and rear doors C², C³, a projecting bottom plate C⁴ and a corresponding top plate C⁵, through both of 45 which plates the rod B extends, forming a guide or axis about which the casing may rotate on its base. Midway between its front and rear doors the casing is vertically divided and braced by a partition C⁶, cut away for the passing of the rod B. The front and rear portions of the apparatus are identical and only the front portion need be described in detail.

55 In this portion are mounted a series of narrow rectangular frames D each having

both top and bottom members provided with a central rib D' to run in corresponding channels or ways D² in the top and bottom of the casing, these channels being 60 formed as shown in Fig. 3, by spaced raised portions or ribs D⁰ extending only to the planes of the front and rear margins of the sides. Each frame is further provided at top and bottom of its inner side with vertical pins E which project into narrow grooves E' in the bottoms of the wider channels or ways D², and these narrower grooves extend forward beyond the line of the casing doors, as seen in Fig. 3, but not to the 65 margin of the projecting top and bottom of the main casing, so that when the doors are open any one of the frames may be drawn forward by its handle, until its pins reach the ends of their grooves and may then 70 swing to the right or left, about these pins as pivots, until its broader side instead of its edge is presented to the front.

Each frame, as shown in Fig. 2, is provided with a series of racks each consisting 80 of two side rods F, F' and a horizontal rod F² hinged at one end to the rod F' and engaging by a spear-like head F⁰ in a corresponding recess in a block F³ carried by the rod F, and normally held in such engagement by a spring F⁴ at the hinged end. Each rod F, F' is pivoted in a disk G fixed to the side wall of the frame and the swinging of the rods is limited, by means of shoulders or stops G', G², to movements 85 between vertical and horizontal positions. When in vertical position it is slightly held, by its own elasticity, behind a rounded stop G³. When it is desired to mount a lace card or the like on the rack, or to remove one, 90 the rod is swung about its hinge and its pointed end is passed through the article or an attachment thereof, and the rod is again restored to position.

Obviously rotation of the casing upon the 100 base and about the guide rod, or axis, brings the rear side of the apparatus to the front, so that the stock in any frame, or any article in any frame in the casing, may be quickly inspected and removed, as a whole 105 or in part, without change of position. It is plain also that the rear faces of goods upon all the many racks may be brought to view by merely swinging the racks forward after inspecting the front faces.

110
What I claim is:

1. The combination with a casing com-

2

rising vertical side walls, a central transverse partition, horizontal top and bottom plates projecting forwardly and rearwardly beyond said walls and provided with spaced parallel raised portions terminating in the planes of the edges of the side walls and having in the intermediate channels narrow, closed, unconnected grooves extending outward beyond said planes, of two opposite series of vertical outwardly sliding rack frames filling the space between said walls, each provided with ribs above and below fitting in the corresponding channels and at its inner side with pins projecting into the corresponding grooves in the plates whereby each frame in sliding between adjacent frames is independently held accurately in its own plane and when fully drawn out is still held in a vertical plane by its pins although free to swing horizontally.

2. In a lace cabinet, the combination with a rectangular casing, of a series of vertical rack frames mounted in the casing to slide horizontally outward and to swing horizontally through an angle of 180° for displaying both faces, of normally vertical racks

mounted in each frame to swing forwardly to horizontal position and comprising two side members, a horizontal bar pivoted at one end to one side member and detachably engaging the other side member, and a spring resisting the swinging of the bar upon its pivot.

3. The combination with a suitable casing, of a series of skeleton rack frames each arranged to slide horizontally outward and swing upon a vertical axis while held by the top and bottom of the frame, racks mounted in said frames and each consisting of normally vertical side rods pivotally attached at their lower ends to the sides of the corresponding frame, and a bar pivoted to the upper end of one of the rods, to swing vertically, and normally engaging and holding the upper end of the companion rod at a fixed distance.

In testimony whereof I affix my signature in presence of two witnesses.

FRANCIS EPPS RICHARDSON.

Witnesses:

W. D. COOK,
W. C. MYERS.
